UNITED STATES PATENT OFFICE.

JOHN P. ECKENROTH, OF CHESTER, PENNSYLVANIA.

ROLLING-MILL FOR BENDING ANGLE OR CHANNEL IRONS INTO DIFFERENT ANGLES.

1,267,194.

Specification of Letters Patent.

Patented May 21, 1918.

Application filed August 2, 1916. Serial No. 112,668.

To all whom it may concern:

Be it known that I, JOHN P. ECKENROTH, a citizen of the United States, residing at Chester, in the county of Delaware, State 5 of Pennsylvania, have invented a new and useful Rolling-Mill for Bending Angle or Channel Irons into Different Angles, of which the following is a specification.

My invention consists of a rolling mill 10 which is adapted to convert an angle iron of right angular form into one of a different angle, the means employed and the operation thereof being hereinafter set forth.

The invention is satisfactorily illustrated 15 in the accompanying drawing, but the important instrumentalities thereof may be varied, and so it is to be understood that the invention is not limited to the specific details shown and described.

20 Figure 1 represents a side elevation of a rolling mill embodying my invention. Fig. 2 represents a longitudinal vertical section thereof.

Fig. 3 represents a top or plan view 25 thereof.

Fig. 4 represents a transverse vertical section on line 4—4 Fig. 3. Fig. 5 represents a transverse vertical section on line 5—5 Fig. 3.

30 Fig. 6 represents a side elevation of the bearing for one of the roll-members employed.

Fig. 7 represents a side elevation of detached portions of the mill, showing the 35 result thereof in converting a right angular channel bar into one with acute angles.

Similar numerals of reference indicate corresponding parts in the figures.

Referring to the drawings:

40 1 and 2 designate pairs of guide rolls on opposite ends of a suitable bed plate or base, and 3 and 4 designate the housings therefor, all of which in general respects are well known in metal rolling mills.

5 Intermediates of said rolls 3 and 4 is the housing 5, in the upper part of which is swiveled the screw or screw shaft 6 on which is fitted the traveler nut 7, which is formed with gudgeons 8 which extend laterally 45 therefrom and are mounted in the rocker or rocking block 9, which latter is formed with gudgeons 10 which extend laterally therefrom and are mounted on the side members of the housing 5.

6 In the rocker 9 are mounted the journals 11 and 12 respectively of the upper ends of

the rolls 13 and 14, which as most plainly shown in Fig. 4 are set in inclined or oblique positions, side by side in vertical direction substantially parallel with each other. 60

On the lower end of the roll 13 is the journal 15 which is mounted in the rocker or rocking block 16 which has on its sides the gudgeons 17 which are mounted in the pillow blocks 18, the latter being supported 65 on and bolted or otherwise secured to the bed plate of the mill.

On the lower end of the roll 14 is the journal 19 which is mounted in the rocker or rocking block 20 which has on its sides the 70 gudgeons 21 which are mounted on the ears 22 of the yokes 23, the latter acting as a pulley block being supported on and bolted or otherwise secured to the bed plate of the mill. 75

The feet 24 of the yokes 23 are vertically slotted to receive the securing bolts 25 of the yokes, the slots being elongated, whereby the yokes may be moved to the right or left, when the block 20 follows the same, 80 and so the roll 14 may be adjusted to and from the roll 13 to change its inclination and so set and adjust its peripheral working face to that of said roll 13. The roll 14 is shorter than the roll 13 whereby the bottom 85 flange of the bar of angle iron to be bent can pass under the end of said roll 14, while the side flange of said bar can pass between the two rolls in contact therewith as shown in Fig. 4. As the yokes are open being 90 somewhat of U-shape, the bar of angle iron can pass through them in their passage in part under one roll, and in part between the two rolls.

The screw shaft 6 and the connections intermediate of the same and the rolls serve to change the angularity of the latter without requiring a separate device for each roll to effect such change. 95

The operation is as follows:— 100

A bar of angle iron is passed between the pair of rolls 1, and guided by the rollers 26 on the bed plate is passed between the rolls 13 and 14 in frictional contact therewith, whereby owing to the inclination of the latter, the side flange of the iron is pressed between said rolls and so bent from a right angle to an acute angle or inclination, as shown in Fig. 4. Then the bar is guided by the rollers 27 to the pair of rolls 2 between the base flange of the bar, while the inclined flange of the bar runs freely on the side of 110

the upper member of the pair of rollers, as shown in Fig. 5, the bar thus being directed from the mill.

The members of each pair of rolls 26 and 5 27 are adjustable to and from each other by means of the series of openings 28 in the frame of the mill to receive the axles of said rolls relatively to the width of the angle or channel iron passing through the mill.

10 By adjusting the traveler nut to the right, it is possible to change the right angle of a bar into an obtuse angle, and this may be accomplished as in converting said right angle into an acute angle during the passing 15 of the bar through the mill.

If it is desired to change the angles of bars of channel irons, the bar is passed through the rolls and then reversed, and thus again passed through the rolls, and thus 20 both side flanges or sides are bent forming either acute or obtuse angles, as will be apparent on reference to Fig. 7, or if desired, one angle may be made acute, and the other angle may be made obtuse.

25 Having thus described my invention what I claim as new and desire to secure by Letters Patent, is:—

1. In a rolling mill, a pair of bending rolls, a rocker block on the frame of the mill having the axes of both rolls mounted thereon, a traveling nut with which said block is rotatably connected, and a screw shaft on which said nut is fitted whereby both rolls may be simultaneously adjusted 35 by the operation of said rocker block.

2. In a rolling mill, a pair of bending rolls, a rocker block mounted on the frame of the mill and having the upper axes of both rolls journaled in said block, a screw 40 shaft on said frame of the mill, a traveling nut on said shaft, and gudgeons on said nut being pivotally mounted on said rocker whereby the operation of said screw both 45 rolls may be simultaneously changed together in angularity.

3. In a rolling mill, a pair of bending rolls of differential length, rocker bearings

for the upper and lower axes of said rolls, and pillow blocks on the frame of the mill in which the bearings for the lower axes of 50 said rolls are mounted, one of said pillow blocks being of open form adapted to permit an angular bar to pass through the same in reaching said rolls and leaving the same.

4. In a rolling mill, a pair of bending 55 rolls disposed substantially parallel with each other, a single rocker support for the upper axes of said rolls, separate rocker supports for the lower axes of said rolls, a single screw shaft on the frame of the mill, 60 and a traveling nut on said shaft, said nut having thereon gudgeons which are rotatably mounted in said single rocker support.

5. In a rolling mill, a pair of bending 65 rolls, a single rocker support for the upper axes of said rolls, separate rocker supports for the lower axes of said rolls, a single screw shaft on the frame of the mill, a traveling nut on said shaft, said nut having thereon gudgeons which are rotatably 70 mounted in said single rocker support, and guide rollers on the frame in the advance and rear of said bending rolls, the bed plate of said frame having therein a series of transversely extending openings in which 75 said guide rollers may be correspondingly adjusted.

6. In a rolling mill, a pair of bending rolls, a rocker block on the frame of the mill and having the upper axes of said rolls 80 journaled in said block, rocker blocks on said frame having the lower axes of said rolls mounted therein, a pillow block on which one of the lower rocker blocks is mounted, and yokes having eyes on which 85 the other lower block is mounted, said yokes being of open form admitting an angle bar to be rolled to pass through said yokes in reaching and leaving said rolls.

JOHN P. ECKENROTH.
